FRED A. RUMNEY, OF CAMBRIDGE, MASSACHUSETTS, ASSIGNOR TO UNITED SHOE MACHINERY CORPORATION, OF PATERSON, NEW JERSEY, A CORPORATION OF NEW JERSEY.

EYELET RESERVOIR.

1,409,201.

Specification of Letters Patent. Patented Mar. 14, 1922.

Application filed July 21, 1920. Serial No. 397,923.

To all whom it may concern:

Be it known that I, FRED A. RUMNEY, a citizen of the United States, residing at Cambridge, in the county of Middlesex and 5 State of Massachusetts, have invented certain Improvements in Eyelet Reservoirs, of which the following description, in connection with the accompanying drawings, is a specification, like reference characters on the 10 drawings indicating like parts in the several figures.

This invention relates to reservoirs for supplying fasteners and more particularly for supplying twin eyelets. A twin eyelet 15 is characterized by having two barrel portions side by side and adjoining a common flange or base portion. Eyelets of this type are used extensively for anchoring hooks and eyes to articles of wearing apparel, and 20 many manufacturers of wearing apparel are equipped with eyeleting machines by which twin eyelets are applied to anchor hooks and eyes as aforesaid.

Heretofore the supplying of twin eyelets 25 to the setting mechanism has been unreliable and in many instances the hopper has failed to maintain a supply commensurate with the number of eyelets used, with the result that from time to time the raceway has become 30 empty and it has been necessary to discontinue the setting of eyelets and to operate the brush, or whatever feeding device is provided in the hopper, for a period sufficient to recharge the raceway. This condition 35 obviously restricts the output of the machines and thereby causes an increase in the cost of eyeleting. Difficulties due to feeding twin eyelets from a hopper into a raceway are accentuated by the peculiar form of the 40 eyelets which prevents too many of them from assuming the position necessary to enable them to pass through the outlet port of the hopper. In order to discharge a twin eyelet from the hopper it is necessary for the 45 eyelet to take a position such that one of its barrels will follow the other through the outlet port, and since a relatively large portion of each eyelet trails after the leading barrel it is retarded and disarranged by the 50 brush or other feeder and also by the eyelets remaining in the hopper so that even though an eyelet may once take the correct position for passing through the outlet port its position is, more often than not, changed so 55 that its discharge is prevented.

In view of the conditions and difficulties above mentioned an object of the present invention is to provide an improved hopper by which twin eyelets may be supplied at a greater rate than they have been by hoppers 60 as heretofore constructed. Accordingly a feature of the invention consists in providing a hopper with an interior guard formed and arranged to facilitate the discharge of eyelets. This guard is preferably arranged 65 adjacent to the outlet port and is preferably formed so as to shed immediately any eyelet that may be temporarily arrested by it. Its shedding effect, in many cases, results quickly in positioning the eyelet correctly 70 for discharge. In any event it promptly clears the way for other eyelets approaching the outlet port so that in either case the shedding effect prevents an accumulation of eyelets such as to obstruct other eyelets that 75 might pass through the outlet port.

According to the construction shown by the accompanying drawings the shedding of the eyelets is obtained by making the guard slightly thicker than the space between the 80 barrels of an eyelet and by rounding the advance end of the guard so that eyelets that are temporarily arrested by it will rock thereon to one side or the other, as the case may be, and thus clear themselves from the 85 guard either by taking the correct position for discharge or by advancing with the mass of eyelets remaining in the hopper. The feeding of the eyelets and the clearing from the guard may be accelerated by a movable 90 brush arranged in the hopper.

The foregoing features and others are illustrated by the accompanying drawings and are hereinafter described and claimed.

In the drawings,

Fig. 1 represents a plan view partly in section of a hopper constructed in accordance with this invention and provided with a raceway and with a brush for agitating the eyelets therein;

Fig. 2 is a perspective view including a fragment of the hopper and a fragment of the raceway, a small portion of the annular wall of the hopper being broken out to disclose the guard leading to the outlet port;

Fig. 3 is a perspective view looking upwardly at a fragment of the hopper including the outlet port and the guard leading thereto.

The hopper has a substantially circular bottom wall 10 on which the eyelets are supported, and a detachable housing comprising an annular side wall 11 and top wall 12. 5 This housing may conveniently be made of a single stamping of sheet metal and may be fastened to the bottom 10 by any suitable means such as bolts 13 extending through holes in the bottom and having heads 14 10 anchored to the wall 11.

The raceway 15 communicates with an outlet port in the annular wall 11, and its channel 16 is of a suitable width to receive the barrel 17 of twin eyelets such as those 15 represented in Fig. 1. Each eyelet comprises a substantially flat base or flange 18 and two barrels 17 projecting therefrom in parallel relation so that they may follow one after the other through the channel of the 20 raceway while their bases or flanges 18 rest on the bottom of the raceway.

The outlet port has a relatively wide portion 19 at the bottom and a relatively narrow portion 20 above, the wide and narrow 25 portions corresponding respectively to the base and barrel portions of the eyelets. This port is preferably oblique relatively to the wall in which it is formed, in order to obtain the maximum rate of discharge of eyelets 30 due partly to inclining the hopper and the raceway and partly to propelling the eyelets toward the outlet port by a rotary brush 21 which may be driven by any suitable means and which preferably would be rotated continuously in the direction indicated by the 35 arrow in Fig. 1. As the eyelets approach the outlet port they are guided to it or deflected away from it, as the case may be, by a guard which stands in the path of the brush 21. The invention is not restricted to 40 any one form of guard but I have found that by making it in the form of a tongue 22, as shown, very satisfactory results may be obtained, and such construction is economical 45 from the manufacturing standpoint. This tongue as shown is riveted to the annular wall 11 and projects inwardly in oblique relation so as to lie substantially parallel and in confronting relation to the oblique 50 surface 23 of the outlet port. The tongue and the surface 23 therefore constitute a channel leading to the channel 16 of the raceway and extending tangentially to the circular path of the tips of the brush 21 so 55 as to utilize the propelling action of the brush to the greatest advantage to discharge the eyelets through the outlet port. As shown by Fig. 3 the tongue 22 occupies the same plane as the relatively narrow 60 upper part 20 of the outlet port and is entirely above the relatively wide lower part 19 of said port. Consequently the bottom surface of the tongue is spaced from the bottom 10 of the hopper so as to overlie and 65 clear the flanges of the eyelets that are cor-

rectly positioned for discharge. The tongue is thicker than the space between the two barrels of an eyelet so that an eyelet would not be capable of straddling it or otherwise becoming permanently caught. Furthermore the tip 24 of the tongue is preferably rounded to semi-cylindric form so that an eyelet that is temporarily arrested by it will rock on the rounded surface and clear itself 75 immediately from the path of other eyelets approaching the outlet channel. The shedding effect of the tongue is also obtained in part by restricting the latter to a thickness no greater than the distance between the centers of the barrels of an eyelet. When an 80 eyelet is temporarily arrested by the tongue as shown in Fig. 1 its two barrels bear on the rounded tip 24 while its base lies on the bottom of the hopper. If the arrested eyelet rocks to the right it will enter the outlet channel in the correct position for discharge but otherwise it will rock to the left and will immediately escape from the tongue so as to give the next succeeding eyelet an opportunity to enter the outlet channel with 85 or without a rocking motion to place it in the right position at the entrance to the channel.

One important advantage of the construction shown is that the tongue increases the rate of discharge by correcting the positions 90 of a large number of eyelets that would otherwise be sufficiently out of position to be incapable of passing through the outlet port, while another important advantage of the tongue is that its shedding effect accelerates the escape of eyelets that have been 95 temporarily arrested thereby so that the entrance to the outlet channel will never be obstructed for a long enough period to prevent the raceway from remaining charged to 100 its full capacity.

Having thus described my invention, what I claim as new and desire to secure by Letters Patent of the United States is:

1. A hopper for supplying twin eyelets, having an outlet-port, and means in the hopper arranged to prevent all but correctly-positioned eyelets from entering said port, said means being thicker than the space between the barrels of an eyelet so that the 115 latter will be incapable of straddling said means.

2. A hopper for supplying twin eyelets, having an outlet-port, and a guard arranged in the hopper so as to prevent all but correctly-positioned eyelets from entering said port, said guard being thicker than the space between the barrels of an eyelet so that the latter will be incapable of straddling the 120 guard.

3. A hopper for supplying twin eyelets, having an outlet-port, and a tongue arranged in the hopper so as to guide correctly-positioned eyelets to said port and to prevent all other eyelets from obstructing the port, 130

the extremity of said tongue being thicker than the space between the barrels of an eyelet.

4. A hopper for supplying twin eyelets, having an oblique outlet-port, and an oblique guard in the hopper arranged to guide correctly-positioned eyelets into the port and to prevent all other eyelets from obstructing the port, said guard being thicker than the space between the barrels of an eyelet.

5. A hopper for supplying twin eyelets, having an annular wall and an outlet-port therein, the latter having an oblique surface, and an oblique tongue arranged in the hopper in confronting relation to said surface and spaced therefrom so as to form an oblique channel of a width slightly greater than the diameter of one of the eyelet-barrels, the thickness of said tongue being greater than the space between the barrels of an eyelet.

6. A hopper for supplying twin eyelets, having an annular wall and an outlet-port therein, and a guard arranged in the hopper so as to form, conjointly with said wall, a channel leading to said port to guide the barrels of the eyelets, said guard being thicker than the space between the barrels of an eyelet, and means arranged to propel the eyelets so that those lying against the advance end of the guard will be removed therefrom.

7. A hopper for supplying twin eyelets, having an outlet-port in one wall, a tongue extending inwardly from said wall adjacent to said port so as to guide correctly-positioned eyelets to the port and to prevent all

other eyelets from obstructing the port, said tongue having a rounded tip of a diameter greater than the space between the barrels of an eyelet so as to shed promptly an eyelet whose barrels are temporarily arrested thereby.

8. A hopper for supplying twin eyelets, having an outlet port, means including a brush arranged to propel the eyelets toward said port, and a guard in the path of said brush and arranged to prevent incorrectly positioned eyelets from obstructing said port, said guard being thicker than the space between the barrels of an eyelet and having a rounded eyelet-arresting surface formed and arranged to shed all eyelets pressed against it by the brush so that such eyelets will be correctly positioned and guided thereby to the port or else deflected into the mass of eyelets remaining in the hopper.

9. A hopper for supplying twin eyelets, having a bottom wall and an annular wall, the latter wall having an outlet port relatively wide at the bottom and relatively narrow above to emit eyelets resting on their flange-ends, and a tongue extending inwardly from the narrow part of said port and spaced from said bottom wall so as to overhang and clear the flanges of eyelets entering said port, the tip of said tongue being formed and arranged to shed eyelets so as to position them correctly for entrance into said port or else to deflect them into the mass of eyelets remaining in the hopper.

In testimony whereof I have signed my name to this specification.

FRED A. RUMNEY.
